VEHICLE BODY

Harvey L. Widgren, 1044 S. Grevillea, Inglewood, Calif. 90301, and Paul E. Adams, 10320 Rossbury Place, Los Angeles, Calif. 90064

Filed Sept. 30, 1971, Ser. No. 185,486

Term of patent 14 years

Int. Cl. D12—II

U.S. Cl. D90—8 A

FIG. 1.

FIG. 2.

FIG. 1 is a front perspective view of a vehicle body showing our new design; and

FIG. 2 is a rear perspective view thereof.

The broken lines shown in FIGS. 1 and 2 are for illustrative purposes only.

We claim:

The new and ornamental design for a vehicle body, as shown and described.
